APPARATUS FOR SEALING CANS AND
THE LIKELynn E. Davies, Park Ridge, Ill., assignor to White
Cap Company, Chicago, Ill., a corporation of
Delaware

Application April 21, 1938, Serial No. 203,425

7 Claims. (Cl. 113—27)

This invention relates to improvements in apparatus for the hermetic sealing of containers of various sorts, particularly metallic cans of the kinds generally used for the preservative packaging of foodstuffs and the like.

It has long been recognized as desirable in the commercial canning of vegetables, fruits, meat products, and the like, to obtain within the sealed package a sub-atmospheric pressure. One of the important purposes which this serves is that of affording means for ascertaining whether or not the package is sealed or closed air tight when it is inspected at the cannery, and thereafter to afford an indication in case fermentation takes place within the sealed package.

A particular object of the invention is the provision of a mechanism whereby closures may be applied to containers of various sorts with accuracy and certainty incident to the uninterrupted progressive movement of the containers past the closure-applying station with great rapidity.

Another object of the invention is the provision of improved apparatus for rapidly feeding and applying a series or succession of closure caps, tops or heads to a series of containers.

Yet another object is the provision of improvements in apparatus for applying closures to packing vessels.

Other and further objects of the invention will be pointed out or indicated hereinafter, or will be apparent to one skilled in the art from the ensuing explanation or from actual use of the invention in practice.

For the purpose of aiding in an explanation of the invention, I show in the accompanying drawings forming a part of this specification, and hereinafter described, certain apparatus and devices serving to exemplify embodiments and practice of the invention. It is to be understood, however, that these are presented merely by way of illustration, and hence are not to be construed in any fashion for the purpose of limiting the appended claims short of the true and most comprehensive scope of the invention in the art.

In said drawings,

Fig. 1 is a longitudinal sectional elevation of a machine for applying and hermetically sealing heads on metallic cans of conventional type and effecting evacuation of air from same;

Fig. 2 is a section similar to Fig. 1 but showing only a portion of the machine, on a larger scale, and serving to illustrate certain details of the mechanism for feeding the can heads to the bodies;

Fig. 3 is a detail on a still larger scale serving to

illustrate the relationship of the can body to the head at the time of first contact;

Fig. 4 is a top view, taken on line 4—4 of Fig. 1, showing the head feed and applying mechanism, some of the parts being broken away;

Fig. 5 is a detail serving to show the relationship of the can body and head at a time in the course of the application of the head to the body subsequent to that illustrated in Fig. 3;

Fig. 6 serves to illustrate the relative position of can head and body at an ensuing time.

The improvements in apparatus constituting my invention consist in various new constructions and organizations of elements and parts which can be explained more quickly and clearly by reference in detail to the accompanying drawings than by a general description.

The machine shown in Fig. 1 is, in general, of the type forming the subject matter of U. S. Letters Patent Nos. 1,920,539 and 2,041,891, granted to White Cap Company, the assignee of this present invention. It comprises a housing 20 having side walls 21 which extend downwardly at opposite sides of a traveling conveyor 22 which, by means of appropriate mechanism, is moved in the direction indicated by the feathered arrow, so that it travels through the tunnel-like enclosure formed by the housing. Disposed within and journaled on the housing are a main sheave 24 and, at opposite sides of the conveyor 22, various guide sheaves 25, 26, 27, 28 and 29, and on these sheaves are entrained lateral holding belts 30, one at each side of the housing, which are guided by the sheaves 25, 26 and 27 in such relationship that they just over the conveyor in the distance between the sheaves 25 and 27.

Within the portion of the housing adjacent its entry end (viz., the left hand end of Fig. 1) is disposed a steam distributor 31, which is a hollow casing into which hot dry steam is supplied through an inlet 31a (see Fig. 2), said casing having a bottom wall 31b overlying the conveyor 22. This steam distributor forms part of the subject matter of U. S. Letters Patent No. 2,107,237, granted February 1, 1938, to my assignee, White

Cap Company, and is therein described in further detail. Part of the hot steam which is supplied to the steam distributor 31 is emitted within the housing through the outlet 31c, so that a blanket of hot vapor is maintained below the wall 31b and forwardly therefrom. The wall 31b is maintained at high temperature by the hot steam which is supplied to the steam distributor, as is also the distributor's top wall 32.

Adjacent opposite sides of the top wall 32 are upstanding guide bars 33 (see Fig. 4), and rest-

ing on these and spaced upwardly from but parallel to the wall 32, is a head holder comprising a plate 34 which is adjustably held in position by means of cap screws 35 seated in the side frames of the distributor casing, and which carries four guide posts 36 disposed equidistantly around a circular aperture 34a in said plate. The diameter of said aperture 34a is slightly less than the distance between a pair of parallel slide bars 37 which travel alongside the guide bars 33 in the space between the plate 34 and the wall 32, said slide bars being carried on a yoke 38 and held in parallel relationship by a strut 39 and running between rollers 40 on the plate 34 and rollers 41 on the steam distributor casing. The slide bars 37 carry a pair of lower pallets 42 and a pair of upper pallets 44, which extend inwardly beyond the periphery of the aperture 34a. The upper pallets 44 are spaced above the lower pallets 42 a distance equal to the thickness of a can head (see Fig. 2). The slide bars are normally held in the elevated or retracted position, illustrated in Figs. 2 and 4, by a spring 45, and when in said position, the lower pallets 42 are within the area of the aperture 34a (but below the plate 34) and the upper pallets 44 are retracted to a position clear of said aperture. The yoke 38 is connected to the movable core 46 of a solenoid 47 by means of a thrust rod 48, lever 49, and link 50, and when the coil of the solenoid 47 is energized, the core 46 is drawn upwardly, the lever 49 is swung on its pivot, and the yoke 38 and slide bars 37 are moved forwardly or downwardly, parallel with the wall 32, to a position where the lower pallets 42 are removed from below the area of the aperture 34a, while the upper pallets 44 are moved to a position below the area of said aperture. A stack of can heads H being disposed between the posts 36, by which they are guided so as to move into the aperture 34a by influence of gravity, and with the lowermost head resting on the pallets 42, forward movement of the slide bars 37 will operate to withdraw the pallets 42 from below the lowermost can head of the stack, and at the same time intrude the upper pallets 44 between it and the next higher can head. Accordingly, when the lower pallets 42 are sufficiently withdrawn, the lowermost can head will drop downwardly from the aperture 34a onto a pair of parallel, slightly elevated ridges 32a which are formed on the wall 32 and form a sloping track on which the can head so released slides downwardly. At this time the remainder of the stack is supported on the upper pallets 44, and remains so supported until the slide bars 37 are retracted by spring 45 to withdraw those pallets from below the stack, whereupon the stack feeds downwardly until the lowermost can head comes to rest upon the lower pallets 42.

At the lower end of the wall 32, which forms the slideway or trackway for the can heads, are carried a pair of stop members 51, which project upwardly from the trackway and are spaced apart a distance slightly less than the full diameter of a can head so that a can head which has slid down the slideway is arrested by said stops in approximately the position designated by the dotted circle H' in Fig. 4. In this position the rearward portion of the can head is still supported on the slideway 32 but its forward portion extends downwardly and forwardly beyond the lower terminus of said slideway, as seen in Figs. 2 and 4. In said position, the forward portion, which is now the lowermost portion, of said

can head is at an elevation below the bottom wall 31b of the steam distributor. Mounted at the sides of the wall 32 are a pair of light leaf springs 52 which may be flexed upwardly and downwardly, and at its lower end each of these springs carries a detent member 54, which is positioned slightly rearwardly from the associated stop 51 and juts over the pathway of the can head, which pathway at this point is bounded by guide strips 55, that are in alignment with the slide bars 37. These detent members 54 keep the can head from jumping over the stops 51 until it is properly withdrawn.

Below or forwardly from the stack plate 34, a bridge member 56 extends across and in spaced relationship to the slideway, being connected at its opposite sides to the spacer rails 33. This bridge member carries a forwardly and downwardly extending bracket 57, and straddling this extension are the legs of a bifurcated yoke 58 which are pivoted on a pintle 59 that is seated in the extension 57. Straddling the legs of the yoke 58 are the legs of a second bifurcated yoke 60, which legs are also journaled on the pintle 59. A stop pin 61 forms a rest for said yokes when they are in their lowermost positions, and the yoke 60 is urged downwardly by a leaf spring 62. Hereinafter the yoke 58 will be referred to as the rearward yoke and the yoke 60 as the forward yoke. These yokes may swing on their common pintle independently of each other, and at their forward or lower ends they carry rollers 64 and 65 respectively. These rollers are long enough to span a substantial portion of the width of the can head and their disposal is such that they are below the forward end of the slideway and beyond the stops 51, the rearward roller being so located that when its yoke is supported on the pin 61, its periphery will be approximately tangent to the sloping plane of the upper surface of the rim of the can head which rests upon the slideway and at a distance forwardly from the stops 51 such that it lies above the upper surface of the rim portion of the can head which is in engagement with the stops 51. The forward roller 65 occupies a position somewhat in advance of the roller 64 with the low point of its periphery at an elevation above the conveyor 22 somewhat less than the combined height of a can body with a head resting thereon.

Forwardly beyond the roller 65 is the head pressing mechanism, shown in side elevation in Fig. 1. It is, in general, of the type illustrated in the above mentioned Patent No. 2,041,891. It includes the main sheave 24, which is carried on the actuating shaft 70, and a broad endless belt 71 which is entrained on said sheave 24 and on a rear sheave 72 which is located so that said belt passes in close proximity to the arc in which the forward roller 65 swings. The bottom flight of the belt 71 is guided and held down by a divided shoe, or pair of shoes, comprising a rear section 74 and a forward section 75, carried respectively on brackets 82 and 77. By suitable driving connection to shaft 70, sheave 24 is rotated in the direction indicated by its arrow to move the belt 71 at the same linear speed as the conveyor 22. The lower flight of the belt 71 is guided by the shoes so that its under surface is maintained at proper distance or distances from the conveyor 22 to effect the proper seating of the can head, as hereinafter explained.

The apparatus described above is adapted or adaptable for use in applying can heads to various kinds of can bodies. It is to be understood,

however, that by suitable modification in details, the apparatus may be similarly employed for the application of closure caps of various kinds to other sorts of receptacles.

In applying heads of the kind above described to can bodies by operation of the apparatus above described, the bodies, suitably filled, are placed in a series on the conveyor 22, and by said conveyor are carried into the tunnel of the housing 20, the conveyor being operated with a continuous movement. The steam distributor 31 is kept supplied with hot steam, whereby its lower wall 31b is maintained at a high temperature, so that the mouth portions of the cans, which travel therebelow, are subjected to radiant heat therefrom. At the same time, the hot steam emitted through the outlet 31c displaces air from beneath the rearward portion of the wall 31b and keeps the space, through which the mouth portions of the cans travel, filled with an atmosphere of hot vapor which surrounds also the lower end of the runway 32 and the closure-applying instrumentalities associated therewith. Hot steam within the steam distributor 31 maintains the top wall 32 also at high temperature, preventing any condensation of moisture thereon.

As a can progresses in the housing 20, it passes between the rearward ends of the laterally disposed belts 30, which belts are guided in converging relationship from the sheaves 28 to the sheaves 27, at which latter point they are sufficiently close together to engage opposite sides of the can and hold it securely against shifting or tilting and in properly centered position on the conveyor. It will be observed that the lower flights of the belts 30, which thus grasp the can between them, are elevated but a short distance above the conveyor 22 so that they grasp the can at only a short distance above its bottom, where the body wall is well braced by the bottom and hence qualified to withstand the lateral pressure of the belts 30 without deformation.

The belts 30 are transmitted at the same rate as the conveyor 22; and, with the conveyor, carry the can past the portion 99a of a switch lever 99, which portion 99a is normally held slightly in the path of the cans by a spring 99c. Consequently, when the advancing can strikes the portion 99a, it swings the lever 99 outwardly on its pivot 99b, and by means of a connection 99d closes a switch to the solenoid 47. The solenoid instantly operates the slide bars 37 to deliver the lowermost can head from the stack onto the runway 32 which is at an inclination such that the head immediately slides downward until arrested by the stops 51 with its forward margin projecting downwardly and forwardly from the runway and under the roller 64.

The relationship of the head H' in reference to the approaching can body B is illustrated in Fig. 3. It will be observed that the lower terminus of the head wall 104 is somewhat below the level of the body flange 112, and that the head surface 102 lies in a sloping position in the path of the body flange. Consequently, as the can advances, its flange 112 engages the surface 102 of the head, and due to the fact that the head is held against advancing by the stops 51, swings the forward margin of the head upwardly, the rear margin of the head meanwhile resting on the runway 32. As soon as the margin of the head flange surmounts the upper limits of the stops 51, the head is free to travel along with the can, which is still pushing against the sur-

face 102. However, the weight of the roller 64 exercises a restraint or braking effect on the head, with the result that when the rear margin of the head drops off of the lower terminus of the runway 32, the margin of the flange 112 is past the lower margin of the head wall 104, and the head has advanced so that the roller 64 is well over the body, and the roller 65 is over the forward portion of the body. Consequently, immediately that the rear margin of the head drops off the end of the runway, the head and body are in the proper relative positions such that the centering boss of the head will enter the upper end of the body when the head is instantaneously snapped down onto the body by the pressure of the rollers 64 and 65.

Incident to the progressive movement of the open body through the hot vapor atmosphere, the air within the unfilled head space of the body is displaced by the hot vapor, and likewise, during the movement of the head down the lower part of the runway and into position on the body, the air has been displaced from its lower surfaces and channels by the hot vapor. As a consequence, when the head comes to rest on the body as above described, the head space is filled with hot vapor in place of the air which has been removed. The body with the head thereon is carried forwardly by the conveyor 22 and passes under the pressing belt 71, whereby the head is pressed down onto the body, thereby forcing the flanges 105 and 112 closer together and causing the shoulder 111 to be intruded into the plastic fillet or sealing gasket 107 carried by the head. After passing out of the housing 21 the head may be affixed to the body by a double seaming operation performed in a can header of conventional type.

What I claim is:

40. 1. In a closure applying apparatus having a conveyor for moving containers progressively, a runway sloping at an angle such that closures may slide down it by gravity and having its lower end arranged over the path of the containers, and a non-yielding stop disposed adjacent the lower end of the runway and projecting upwardly therefrom in position to engage a lateral portion of a closure thereon and detain it stationarily in sloping position with its forward portion in position to be engaged and lifted by an advancing container, the height and arrangement of the stop being such as to permit the lateral portion of the closure to pass over it when the forward portion of the closure is swung upwardly from the runway by the advancing container.
45. 2. In a closure applying apparatus having a conveyor for moving containers progressively, a runway sloping at an angle such that closures may slide down it by gravity and having its lower end arranged over the path of the containers, a non-yielding stop disposed adjacent the lower end of the runway and extending upwardly therefrom in position to engage a lateral portion of a closure thereon and detain it in sloping position with its forward portion in position to be engaged and lifted by an advancing container, the height and arrangement of the stop being such as to permit the lateral portion of the closure to pass over it when the forward portion of the closure is swung upwardly from the runway by the advancing container.
50. 3. In a closure applying apparatus having a conveyor for moving containers progressively, a runway sloping at an angle such that closures may slide down it by gravity and having its lower end arranged over the path of the containers, a non-yielding stop disposed adjacent the lower end of the runway and extending upwardly therefrom in position to engage a lateral portion of a closure thereon and detain it in sloping position with its forward portion in position to be engaged and lifted by an advancing container, the height and arrangement of the stop being such as to permit the lateral portion of the closure to pass over it when the forward portion of the closure is swung away from the runway by the advancing container, and upwardly yieldable detent means arranged for cooperation with the closure adjacent the stop to restrain it against being moved over the stop by gravity.
55. 4. In a closure applying apparatus having a conveyor for moving containers progressively, a runway sloping at an angle such that closures may slide down it by gravity and having its lower end arranged over the path of the containers, a non-yielding stop disposed adjacent the lower end of the runway and extending upwardly therefrom in position to engage a lateral portion of a closure thereon and detain it in sloping position with its forward portion in position to be engaged and lifted by an advancing container, the height and arrangement of the stop being such as to permit the lateral portion of the closure to pass over it when the forward portion of the closure is swung away from the runway by the advancing container, and upwardly yieldable detent means arranged for cooperation with the closure adjacent the stop to restrain it against being moved over the stop by gravity.
60. 5. In a closure applying apparatus having a conveyor for moving containers progressively, a runway sloping at an angle such that closures may slide down it by gravity and having its lower end arranged over the path of the containers, a non-yielding stop disposed adjacent the lower end of the runway and extending upwardly therefrom in position to engage a lateral portion of a closure thereon and detain it in sloping position with its forward portion in position to be engaged and lifted by an advancing container, the height and arrangement of the stop being such as to permit the lateral portion of the closure to pass over it when the forward portion of the closure is swung away from the runway by the advancing container, and upwardly yieldable detent means arranged for cooperation with the closure adjacent the stop to restrain it against being moved over the stop by gravity.
65. 6. In a closure applying apparatus having a conveyor for moving containers progressively, a runway sloping at an angle such that closures may slide down it by gravity and having its lower end arranged over the path of the containers, a non-yielding stop disposed adjacent the lower end of the runway and extending upwardly therefrom in position to engage a lateral portion of a closure thereon and detain it in sloping position with its forward portion in position to be engaged and lifted by an advancing container, the height and arrangement of the stop being such as to permit the lateral portion of the closure to pass over it when the forward portion of the closure is swung away from the runway by the advancing container, and upwardly yieldable detent means arranged for cooperation with the closure adjacent the stop to restrain it against being moved over the stop by gravity.
70. 7. In a closure applying apparatus having a conveyor for moving containers progressively, a runway sloping at an angle such that closures may slide down it by gravity and having its lower end arranged over the path of the containers, a non-yielding stop disposed adjacent the lower end of the runway and extending upwardly therefrom in position to engage a lateral portion of a closure thereon and detain it in sloping position with its forward portion in position to be engaged and lifted by an advancing container, the height and arrangement of the stop being such as to permit the lateral portion of the closure to pass over it when the forward portion of the closure is swung away from the runway by the advancing container, and upwardly yieldable detent means arranged for cooperation with the closure adjacent the stop to restrain it against being moved over the stop by gravity.
75. 8. In a closure applying apparatus having a conveyor for moving containers progressively, a runway sloping at an angle such that closures may slide down it by gravity and having its lower end arranged over the path of the containers, a non-yielding stop disposed adjacent the lower end of the runway and extending upwardly therefrom in position to engage a lateral portion of a closure thereon and detain it in sloping position with its forward portion in position to be engaged and lifted by an advancing container, the height and arrangement of the stop being such as to permit the lateral portion of the closure to pass over it when the forward portion of the closure is swung away from the runway by the advancing container, and upwardly yieldable detent means arranged for cooperation with the closure adjacent the stop to restrain it against being moved over the stop by gravity.

3. In a closure applying apparatus having a conveyor for moving containers progressively, the combination of a runway along which closures may be fed to a position over the path of the containers, lateral guide members associated with said runway to guide closures in their movement thereon, a stop carried by one of said lateral guide members and projecting upwardly from the plane thereof and laterally into the path of the closures thereon, said stop being fixed in position to detain a closure on the runway with its forward portion intersecting the pathway of a container therebelow in position to be engaged and swung upwardly by a container advancing in said pathway, said stop being of height such as to permit the closure to pass over it when the forward portion of the closure is swung away from the runway by the advancing container.

4. In closure applying apparatus, in combination, a conveyor for moving containers progressively, a runway along which closures may be fed, non-yielding stops jutting upwardly from the plane thereof and laterally into the path of closures on said runway and cooperating with the latter to sustain a closure stationarily in a sloping position intersecting the path of the containers with its rim in position to be engaged by an advancing container and swung upwardly from the runway sufficiently to surmount said stops and be moved forwardly past the same incident to further progressive movement of the container.

5. In closure applying apparatus, in combination, a conveyor for moving containers progressively, a runway on which a closure may move into proximity to the path of the containers, a non-yielding stop associated with the runway in position to engage a lateral margin of a closure thereon at a point above the plane of the runway and at a substantial distance rearwardly from the forward margin of said closure, said runway and stop being positioned relative to the conveyor so as to hold the closure stationarily in a sloping position intersecting the path

of the containers with its margin in position to be engaged by an advancing container and swung upwardly from the runway sufficiently to permit its moving forwardly over the stop so that the cap may be withdrawn from the runway upon further advance of the container.

6. In closure applying apparatus, in combination, a conveyor for moving containers progressively, a runway along which closures may be fed, a non-yielding stop cooperating with said runway in position to engage a rim portion of a closure thereon at a point above the plane of the runway and to hold the closure in a sloping position intersecting the path of the containers with a portion of the closure in position to be engaged by an advancing container to raise its rim portion sufficiently to ride over the stop incident to further progressive movement of the container, and yieldably mounted means in position to overlap the upper surface of the closure and restrain its rim portion against surmounting the stop until it is forced upwardly by a moving container.

7. In closure applying apparatus, in combination, a conveyor operable to move a container progressively with its upper end in an approximately horizontal plane, a runway arranged to support a closure stationarily above the path of the container in a sloping plane intersecting said horizontal plane, a non-yielding stop associated with the runway in position positively to engage a lateral portion of the closure at a location above the plane of the runway to limit its movement thereon and locate its forward rim in the path of the container, said stop being located in a position where it will be surmounted by the lateral portion of the closure when the latter is swung upwardly from the runway by the advancing container, and an upwardly movable detent spring-pressed to a position to overlap an upper surface of the closure and restrain its lateral portion against surmounting the stop until forced upwardly by an advancing container.
